Patented July 10, 1973

227,683

COMBINATION SANDBOX AND POOL

Walter Mitchko, 337 Elwood Road,
East Northport, N.Y. 11731

Filed Nov. 22, 1971, Ser. No. 201,260

Term of patent 14 years

Int. Cl. D21—01

U.S. Cl. D34—5 F

Fig. 1

Fig. 2

Fig. 3

Fig. 4

FIG. 1 is a top perspective view of a combination sandbox and pool, showing my new design;

FIG. 2 is a side elevational view thereof;

FIG. 3 is an end elevational view thereof; and

FIG. 4 is a plan view thereof.

I claim:

The ornamental design for a combination sandbox and pool, substantially as shown.
